UNITED STATES PATENT OFFICE.

ADOLPH DIRIAN AND WILLIAM BIEL, OF CHICAGO, ILLINOIS.

APPARATUS FOR CHARGING LIQUOR WITH GAS.

1,191,952.

Specification of Letters Patent.

Patented July 25, 1916.

Application filed April 16, 1915. Serial No. 21,824.

To all whom it may concern:

Be it known that we, ADOLPH DIRIAN and WILLIAM BIEL, citizens of the United States, residing at 2440 West Twenty-first Place 5 and 1952 South Springfield avenue, respectively, in the city of Chicago, county of Cook, and State of Illinois, have invented certain new and useful Improvements in Apparatus for Charging Liquor with Gas.

10 The objects of our invention are to introduce the liquid under pressure into a tank, impart a swirling whirling motion to said liquid as it enters the tank and simultaneously therewith inject a jet of highly compressed gas through the swirling stream of liquid so as to thoroughly and intimately mix and mingle the liquid and gas together as they enter the tank and thereby produce high and uniform carbonation of the liquid 15 at an extremely rapid speed. To accomplish these and other objects we have devised a simple and exceedingly efficient apparatus including a pump for the liquid, a mixing tank suitably connected to said pump, by 20 piping, a device within the tank having oblique deflecting or mixing blades or vanes against which the liquid impinges as it flows from the pump piping and an injecting nozzle suitably connected to a source of gas under 25 high compression which directs a jet of gas upon the liquid as it flows from the pump piping and is converted into a swirling whirling stream by the oblique blades or vanes.

30 The manner in which we carry out our improvement will be fully and clearly set forth and described in the following specification and particularly pointed out in the appended claims, reference being had to the 35 accompanying drawings in which a preferred embodiment or adaptation of our improved apparatus for charging liquid with gas is shown.

In the accompanying drawings Figure 1, 45 represents a front elevation of our improved apparatus for charging liquids with gas, a fragment of a conventional form of liquid or beer pump only being shown. Fig. 2 is a top plan view of our improved mixing tank 50 or container with the various piping connected thereto. Fig. 3 is a central vertical section through the mixing tank or container, and also showing the various piping in fragmentary side elevation. Fig. 4, is a 55 fragmentary side elevation of the upper portion of the mixing tank or container, look-

ing at approximately a right angle to the view shown in Fig. 1. Fig. 5 is a horizontal section cutting through the hollow conical mixing device only on line 5—5, Fig. 3. 60 Fig. 6 is an enlarged horizontal section through the entire mixing tank or container and its piping on line 6—6, Fig. 1 and looking downward in the direction of the arrows in said Fig. 1. Fig. 7, is a detached fragmentary perspective view of the cone valve and its shape to illustrate the flat side portion of the valve. Fig. 8 is a vertical central section through the tank or container head or end plate. Fig. 9 is an enlarged 70 horizontal section through the lower portion of the hollow conical mixing device to show the oblique liquid deflecting blades or vanes.

In referring to the preferred embodiment or adaptation of our improved apparatus 75 for charging liquid with gas shown in the accompanying drawings in detail like numerals indicate corresponding parts.

Our improvement in the art of charging liquid with gas briefly stated consists in introducing a stream of liquid under pressure into a suitable tank or container and against oblique deflecting surfaces which impart a swirling motion to the said stream and simultaneously directing a jet of highly compressed gas against the swirling stream so that uniform, even and thorough carbonation of the liquid is effected.

Our improvement as shown in the accompanying drawings and described in the following specification is chiefly used in carbonating beer and similar liquids.

As shown the preferred embodiment of our improved apparatus comprises a mixing tank or container, a pump for the liquid 95 suitably connected by piping to the mixing tank or container and piping for supplying gas under high pressure.

The mixing tank or container consists of a cylindrical body 1, mounted in vertical 100 position on a stand or support 2, a closure plate 3, for the lower end of said body and a head or closure plate 4 for the upper end of said body. The head or upper closure plate 4, is constructed substantially as shown 105 in Figs. 1, 2, 3, 4 and 8, principally Fig. 8, and is provided with an annular flange 5, through which bolts 6 are fitted to detachably secure the head to the body 1, a center vertically projecting valve casing 7 having 110 a tapering valve seat 8, at its lower end which opens into the interior of the tank, a

horizontal hollow portion 9 having an opening 10, extending radially out from and communicating with the interior of the valve casing and terminating at its outer extremity in an enlarged internally screw threaded pipe socket 11, into which a pipe 12 screws which extends from a suitable source of gas under pressure.

An annular collar 13, is fitted within the valve casing through the reduced opening of which the upper portion of a valve stem 14 projects. A truncated conical valve 15 is mounted upon an intermediate portion of the valve stem and is operatively arranged relatively to the valve seat 8. The valve is preferably flattened or cut away on one side, so that the gas passage is never entirely closed as shown at 16 in Fig. 7. The valve 15, is normally maintained in closed position relatively to the valve seat 8, both by gravity and by the tension of a spiral spring 17, arranged in the valve casing and adapted to press down upon a collar 18 on the upper end of the valve stem. The tension of the spring 17 is regulated by a flanged nut 19, fitted in the upper end of the spring and mounted on the lower extremity of a screw bar 20, which is fitted through a screw threaded central opening in a screw cap 21, closing the upper end of the valve casing. A manually operated turning wheel 22, is attached to the upper projecting end of the bar 20, and a stuffing box 23, is arranged on the screw cap to prevent the escape of gas through the upper end of the valve casing. The lower portion of the valve stem depends vertically down within the tank body and carries a float 24 at its lower extremity. The object of the float is to raise the valve 15 as the liquid accumulates in the tank 1, so as to supply a sufficient amount of gas to establish a pressure to prevent the further inflow of liquid.

A hollow conical mixing device or shell is hung pendant from the upper head and depends centrally within the body of the tank or container. The preferable form of mixing device or shell is shown in Figs. 3 and 5 and consists of an upper circular band or ring 25, a lower band or ring 26, and an intermediate tapering wide band 27, which extends between and merges at its respective top and bottom with the bands 25 and 26. Deflecting blades or vanes 28 are arranged within the upper band which extend obliquely, and similar oblique blades or vanes 29 are also arranged in the tapering or cone shaped band 27, as shown in Fig. 9. For some purposes one of these sets of deflecting blades or vanes may be dispensed with, the remaining set being sufficient. The purpose of these blades will be fully set forth farther on. The blades or vanes 29 located in the tapering conical band 27 are preferably four in number and in order to securely fasten

the blades in place the interior of the band 27 is divided into four segmental parts by four equi-distant radial partitions 30 which extend vertically from the top to the bottom of said band 27 and radiate horizontally out from a common center sleeve 31 to the annular tapering wall of the band. The blades 29 are preferably formed in the peculiar curved shape shown in Fig. 9 and are rigidly fastened to the partitions 30 by bolts 75 or rivets 32, or other suitable fastening means.

The valve stem 14 has the lower portion thereof below the cone valve 15, slidably fitted through the sleeve 31, as shown in Fig. 80 3, which thus supports and centers the same.

An indicating gage is arranged in vertical position on one side of the tank or container for indicating the liquid level within the tank which comprises a glass tube 33, a pipe 34 leading from the upper end thereof and connected to the head through which it communicates with the interior of the tank, a shut off valve 35 in said pipe, a short horizontal pipe 36 extending from the lower end 90 of the glass tube 33, to and through the wall of the body of the tank, a shut off valve 37 connected to said pipe 36, and a lower valved blow out nozzle 38, for the gage. A pressure indicating gage 39 is attached to the tank for indicating the pressure within the tank.

The pipe 40 in Figs. 1 and 3 extends to a source of liquid supply and is connected at its outer end to a pipe 41, which extends from a pressure pump 42, to the tank or container. The pipe 40 is provided with a shut off valve 43, and the pipe 41, extends horizontally to one side of the tank or container, then bends vertically up extending along the side of the tank to a point slightly above the head where it bends horizontally in and connects to a hollow horizontal coupling 44, formed in the head. The inner portion of the coupling extends to and communicates with the interior of the mixing shell at the upper end thereof. If desired portions of the pipe 41 may be constructed of suitable flexible hose. A short horizontal pipe 45 extends inwardly from the pipe 41 and connects to the tank or container near the lower end thereof and a three way valve 46 is located at the juncture of said pipes 41 and 45. A shut off valve 47 is also located in the lower horizontal portion of the pipe 41.

An outlet pipe 48 is connected to the tank or container preferably through the lower closure plate 3, as shown in Fig. 3, and extends to any desired receptacle or receiving tank. A shut off valve 49 is placed in this pipe 48.

We prefer to use the gas known as carbonic acid gas and under high pressure and conduct it from a suitable supply receptacle 130

(not shown) through the pipe 12 and socket 11 to a point within the valve casing above the cone valve as shown in Fig. 8. A suitable shut off and regulating valve 50 is placed in the pipe 12 and a gas pressure indicating gage 51 is also connected to said pipe 12. A pipe 52 is connected to the head and is provided with a shut off valve 53, which when open permits the air within the 10 tank or container to be forced out as the liquid enters.

We preferably operate our improved apparatus as follows: The valve 53 being opened and the three way valve 46 being 15 turned to permit the liquid to flow into the tank through the lower horizontal pipe 45, the pump 42 is started and the tank gradually filled with liquid. When the tank is filled to the desired point as indicated in 20 the glass 33 the valve 53 of the air outlet pipe is closed and the three way valve 46 is turned to shut off the pipe 45, and open the passage for the flow of liquid through the upper position of the pipe 41 to and 25 through the coupling 44, and the mixing shell from where it flows downwardly into the tank. At the same time the shut off valve 49 of the outlet pipe is opened permitting the liquid to flow out from the tank 30 and the gas supply valve is opened to allow the gas to pass into the valve casing and thence downward past the cone valve and into the mixing shell. As the liquid enters the mixing chamber it impinges upon the 35 oblique blades or vanes 28 and 29 and is deflected by the same being given a swirling motion, and at the same time the gas issues forth from the lower end of the valve casing under high pressure and contacts, mixes 40 and commingles with the liquid forming an even and uniform mixture and producing perfect and efficient carbonation. The breaking of the stream of liquid by the vanes as described releases and separates 45 some of the gases contained in and forming the liquid and also separates and divides the liquid into a multiplicity of minute particles which readily and easily mix and combine with the carbonic acid gas.

50 While our improvement in the art of charging liquids with gas is designed chiefly for carbonating beer and similar

liquors, it is equally adapted for mixing gas with various other liquids.

While we have illustrated and described 55 a preferred form of construction for carrying our invention into effect, this is capable of a wide range of variation, alteration, modification and change without departing from the spirit of our invention. We therefore, do not wish to be limited to the construction herein shown and described but desire to avail ourselves of all such variations, alterations, modifications and changes as fairly fall within the scope of the ap- 60 pended claims or may be constructed to be within the scope thereof by invoking the doctrine of equivalents.

What we claim is:

1. In an apparatus of the class described, 70 a closed tank, a hollow conical mixing shell hung pendant within the upper portion of the tank, oblique deflecting vanes arranged within the shell, a pipe extending from a source of gas supply, a valve casing connected to said pipe and depending into the tank over the shell, a valve in said casing, controlling the flow of gas, a pipe for supplying liquid and a hollow coupling in the 75 tank connected to said liquid supply pipe 80 and having its inner extremity opening into the shell over the vanes.

2. In an apparatus of the class described, 85 a closed tank, a hollow conical mixing shell hung pendant within the upper portion of the tank, oblique deflecting vanes arranged within the shell, a pipe extending from a source of gas supply, a valve casing connected to said pipe and depending into the tank over the shell, a valve in said casing 90 controlling the flow of gas, a float in the tank having a stem connected to the valve, a pipe for supplying liquid and a hollow coupling in the tank connected to said liquid supply pipe 95 and having its inner extremity opening into the shell over the vanes.

In testimony whereof we have hereunto affixed our names in the presence of two witnesses.

ADOLPH DIRIAN.
WILLIAM BIEL.
